UNITED STATES PATENT OFFICE

FREDERIC J. KREUTZER, OF ELMIRA, NEW YORK, ASSIGNOR TO JAMES MANUFACTURING COMPANY, OF FORT ATKINSON, WISCONSIN, A CORPORATION OF WISCONSIN

DESIGN FOR A FARM BUILDING

Original application filed October 17, 1932, Serial No. 45,386. Divided and this application filed February 9, 1933. Serial No. 47,156. Term of patent 7 years.

DIVISION A

To all whom it may concern:

Be it known that I, FREDERIC J. KREUTZER, a citizen of the United States, residing at Elmira, in the county of Chemung and State of New York, have invented a new, original, and ornamental Design for a Farm Building, of which the following is a specification, reference being had to the accompanying drawing, forming a part thereof.

The accompanying drawing is an isometric perspective of my farm building design.

This application is a division of my application, Serial No. D-45,386, filed October 17, 1932.

I claim:

The ornamental design for a farm building substantially as shown.

FREDERIC J. KREUTZER.
